PRODUCTION OF POLYCARBOXYLIC
ACID PRODUCTS

Robert J. Miller, Berkeley, Calif., assignor to
California Research Corporation, San Fran-
cisco, Calif., a corporation of Delaware

No Drawing. Application October 8, 1947,
Serial No. 778,739

1 Claim. (Cl. 260—342)

1

This invention relates to a new and improved process for the production of tetracarboxylic acid anhydrides and especially to the production of such anhydrides from aromatic compounds having at least two pairs of ortho-positioned aliphatic substituents.

More particularly, the invention provides a new process for producing tetracarboxylic acid anhydrides, such as pyromellitic anhydride by catalytic conversion of alkyl aromatic hydrocarbons having two pairs of ortho-positioned alkyl groups, such as 1,2,3,4 tetra alkyl benzenes; 1,2,4,5 tetra alkyl benzenes, and the like.

Aryl tetracarboxylic acid anhydrides have not been available commercially at reasonably low cost. The relative commercial scarcity of such acid anhydrides is due to various factors. Thus, prior processes for obtaining aryl tetracarboxylic acids have yielded either types of acids which do not form the anhydride readily, if at all, or have given the product in free acid rather than anhydride form.

Conversion from the free acid to the anhydride requires a separate dehydration operation with attendant loss and cost. Other factors frequently responsible for relative scarcity of aryl tetracarboxylic acid anhydrides have been low yields of these products with formation of correspondingly large amounts of impurities which, because of their similarity in chemical and physical properties, create anything but easy purification problems. Expensive reagents heretofore used in the synthesis of such anhydrides also have added significantly to the cost of any potential processes.

An object of this invention is to provide a new and improved process for producing aryl tetracarboxylic acid anhydrides.

Another object is to furnish a process for yielding such anhydrides directly and in relatively high purity.

An additional object of this invention is to provide a process for obtaining aryl tetracarboxylic acid anhydrides in which the carbonyl groups of the anhydrides are directly attached to an aromatic nucleus.

The invention has another object the production of aryl tetracarboxylic acid anhydrides from alkyl aromatic hydrocarbons by oxidation with air or gaseous oxygen.

A further object is to produce pyromellitic anhydride from durene and molecular oxygen.

Compounds from which aryl tetracarboxylic acid anhydrides may be produced in accordance with this invention are characterized by an aromatic nucleus with an even number of at least

6 four aliphatic substituents in ortho-positioned pairs attached to the aromatic nucleus by aliphatic to aromatic carbon to carbon bonds. An odd number of aliphatic or other oxidizable substituents normally destroy the stability of the benzene nucleus and tend to defeat conversion to tetracarboxylic acid anhydrides. Exemplary alkyl aromatic hydrocarbons having the desired characteristics are:

1,2,4,5 tetra alkyl benzene

1,2,3,4 tetra alkyl benzene

20 Durene is a preferred tetra alkyl benzene, although its homologs in which one or more of the above radicals R1, R2, R3 and R4 is ethyl, normal propyl, isopropyl, normal butyl, secondary butyl may be utilized. Higher alkyl radicals are not precluded, but aliphatic groups containing 1 to 4 carbon atoms are preferred since longer chains not only raise the boiling point of the feed to be vaporized, but also increase the heat liberated by the reaction with attendant difficulties in temperature control. The invention embraces other feeds in which two pairs of ortho-positioned aliphatic groups are provided, for example:

1,2 di-acetyl 4,5 dimethyl benzene

1,2,4,5 tetra acetyl benzene

1,2,3,4 tetra hydro-6,7 dimethyl naphthalene   1,4 di-hydro-6,7 dimethyl naphthalene

The invention is illustrated by the production of pyromellitic anhydride from durene or durene-containing hydrocarbon fractions or other homologous polyalkyl benzenes substituted in the 1, 2, 4 and 5 positions. The durene or durene fraction is vaporized; the vapor phase hydrocarbon mixed with oxygen, air or other oxygen-containing gas and the resulting gaseous reaction mix-

ture is contacted with a catalyst comprising vanadium oxide at a temperature in the range of from about 700-1200° F. A preferred catalyst is vanadium oxide supported on an inert carrier, such as silicon carbide or alumina. Under these conditions the durene is catalytically oxidized to form pyromellitic anhydride and water. The main reaction is:

Some over-oxidation may occur to yield carbon dioxide and additional water, together with minor amounts of ring rupture derivatives easily separable from the pyromellitic anhydride.

It has been found that high yields of pyromellitic anhydride are formed in good purity and can be separated readily from the gas stream issuing from the reactor. Proper control of conditions is required to secure the most favorable results. This requires limiting such variables as reactor temperature, air rate, feed rate, air-to-hydrocarbon ratio, nature of the catalyst, amount of catalyst, nature of the catalyst carrier, and particle size of the carrier.

Operable temperature range for effecting the oxidation is limited at the lower extremity by the activity of the preferred catalyst. It is preferred to use as catalyst an oxide of vanadium. Below about 700° F., vanadium oxide is incapable of being reoxidized from its lower to its higher valence states by the use of air alone, and since its function as a catalyst depends upon its ability to freely interchange its valences, temperatures below about 700° F. are not practical. However, other catalysts are also effective in this oxidation which are capable of regeneration from lower to higher oxidation states with air or oxygen at temperatures considerably below this; for example, tin vanadate is most effective in the neighborhood of 550° F. Upper temperature limit is governed by the degree to which the heat of the oxidation reactions can be controlled. At temperatures above about 1470° F., the catalyst mass will fuse and tend to plug the reactor tubes. Above about 1200° F. the pyromellitic anhydride becomes unstable and the resultant yields of product are lowered. For these reasons, it is desirable to make every effort to disperse the heat of the exothermic oxidation reactions.

It has been found that satisfactory temperature control can be obtained by carrying out the oxidation in a reactor resembling a heat exchanger in which the tube bundle is packed with catalyst and constitutes the reactor, and a suitable coolant, such as a molten salt or boiling mercury, is circulated through the shell. By keeping the diameter of the tubes sufficiently small, say, $\frac{5}{8}$ inch inside diameter, satisfactory temperature control has been obtained. With such an arrangement, it has been found that this process can be effected with reactor temperatures (bath temperatures) between 700° F. and 1200° F. However, there is still sufficient heat of reaction to create a local hot spot in each reactor tube which must be controlled by variables other than bath temperature. It is preferred to maintain this hot spot temperature between 800° and 1100° F., the exact figure depending upon other conditions which will become apparent.

The most satisfactory catalyst we have found is one composed primarily of oxides of vanadium

on a carrier of relatively low surface to volume ratio; for instance, vanadium pentoxide coated on a carrier of silicon carbide or alumina such as "Carborundum" or "Alundum," respectively. In order to aid in controlling reaction temperatures, particle size of the catalyst mass should be kept relatively coarse. Mesh sizes from 4 to 10 have proven quite satisfactory.

Use of this type of catalyst limits other variables, such as temperatures and air-to-hydrocarbon ratios. It is necessary to operate with an excess of oxygen over that theoretically required to effect the desired oxidation in order to maintain the catalyst in its higher valence states.

When using air as the source of oxygen, it has been found that this process can be operated with an air-to-hydrocarbon ratio between 20 and 1000 by weight, but preferably to keep it between 30 and 200 to obtain best yields commensurate with high throughput.

Space rate is not particularly critical over a wide range. It is preferred to consider it in terms of air rate and feed rate for a given catalyst tube. For instance, with other variables held constant, the quantity of catalyst in a reactor tube can be varied from about 100 cc. down to 25 cc. without materially affecting yields and conversions. This is because essentially the entire oxidation occurs in the immediate neighborhood of the hot spot, a region varying in depth between a fraction of an inch and several inches. Use of more catalyst is desirable as a safety factor in case of fluctuation in catalyst activity.

In a reactor consisting of a single three-foot tube of $\frac{5}{8}$ inch inside diameter immersed in a cooling bath and packed with 50 to 100 cc. of catalyst, it is preferable to use an air rate between 40 and 70 mols per hour, and a feed rate between 0.05 and 0.3 mol per hour.

Alternatively, a so-called "fluid catalyst" technique and process may be utilized, salient features of which are use of low gas velocities and a powdered catalyst. To avoid undue loss in catalyst activity, it is preferred to use a pulverulent vanadium oxide catalyst in which the support is vanadium metal. (However, vanadium oxide alone or vanadium oxide with other supports are operable.) Desirably, the vanadium oxide is indigenous to the vanadium support. The "fluid catalyst" technique is one in which powdered catalyst is handled like a fluid and is well known for catalytic cracking in the petroleum industry. Such types of processes and fluid powder catalyst handling mechanisms are disclosed in Petroleum Refiner, 1947 Process Hand Book, Section I (Apr. 1947), pages 150-153.

This invention is illustrated in greater detail by the following specific examples:

Example 1

A three-foot long stainless steel tube of $\frac{5}{8}$ inch inside diameter and jacketed with a bath of mercury, the boiling temperature of which is controlled with nitrogen pressure, was charged with 100 cc. of catalyst composed of 5 to 10 mesh "Carborundum" coated with vanadium pentoxide. A $\frac{1}{4}$ inch stainless steel thermowell was inserted up the center of the reactor tube. Liquid durene held at 280° F. was metered through a pumping system at a rate of 31.3 cc. per hour to a vaporizer, where the hot durene contacted a metered stream of air flowing at 53 mols per hour, already preheated to 280° F., and the two components flowed concurrently through the vaporizer at 280° F. so that at the point of exit from the va-

porizer there issued a homogeneous gaseous mixture ready for feeding to the preheat section of the reactor. This consisted of the volume of the reactor tube above the catalyst, which was packed with uncoated silicon carbide and heated to the reactor temperature, e. g., 850° F. The gaseous mixture then passed over the catalyst where a hot spot of 1050° F. developed four inches from the top of the catalyst. Vapors issuing from the reactor passed into two parallel air-cooled condensers, consisting of 30-inch long glass tubes of 2½ inch inside diameter containing four wire screen baffles spaced equidistant along each tube. The pyromellitic anhydride and any other products of low volatility were collected in these condensers as solids. Waste gases from the tubes consisted of spent air, water vapor, CO and CO₂ from the oxidation, traces of other intermediate oxidation products, and about 5% of the pyromellitic anhydride that had been formed. Analysis of condenser products after operation of the unit for one hour showed 22.4 g. of crude pyromellitic anhydride to have been formed from 31.3 cc. (25.3 g.) of durene, or an 89.0 weight per cent yield. The neutral equivalent of this crude product was 55.5 (theoretical, 54.5), indicating a purity of 98.2%.

Example 2

The reactor described in Example 1 was packed with 50 cc. of catalyst instead of 100 cc. All other conditions and equipment were similar, except that durene was pumped at 28.8 cc. per hour. A 93.7 weight per cent yield of crude pyromellitic anhydride of 93.5% purity by neutral equivalent was formed.

Example 3

Conditions and equipment were duplicated in Example 2, except that the bath temperature was increased to 890° F., and durene was added at 29.7 cc. per hour. A 98.5 weight per cent yield of crude pyromellitic anhydride of 92% purity by neutral equivalent was formed.

Example 4

Conditions and equipment were the same as in Example 1, except that 100 cc. of 4 to 6 mesh "Alundum" coated with vanadium pentoxide were used as catalyst in place of Carborundum coated catalyst. Durene was pumped at 30 cc. per hour. A 90.0 weight per cent yield of crude pyromellitic anhydride of 94.4% purity by neutral equivalent was formed.

Example 5

Conditions and equipment were the same as in Example 4, except that bath temperature was held at 850° F., and liquid durene was pumped at 20.7 cc. per hour. A weight yield of 102% of crude pyromellitic anhydride of 94% purity by neutral equivalent was formed.

Example 6

Conditions and equipment were identical with Example 5, except that a water scrubber was attached to the system after the air-cooled condensers, and durene pumped at 19.6 cc. per hour. A yield of pyromellitic anhydride of 103.7 weight per cent was formed from the condensers. An additional 4.7 weight per cent of anhydride was recovered as the free acid from the scrubber solution.

Example 7

Example 2 was duplicated, except that durene was pumped at 48.3 cc. per hour. An 84.7 weight

per cent yield of crude pyromellitic anhydride of 98.1% purity by neutral equivalent was obtained.

Example 8

Example 4 was duplicated except that air was fed at 63 mols per hour, instead of 53, and durene was pumped at 15 cc. per hour with a bath temperature of 890° F. A 102.5 weight per cent yield of 97.3% pyromellitic anhydride was collected.

Example 9

Example 8 was duplicated except that the air rate was decreased to 44 mols per hour, and durene was fed at 30.0 cc. per hour. An 80.0 weight per cent yield of 96.2% pure pyromellitic anhydride was collected in the condensers.

Example 10

The same equipment and catalyst as in Example 4 were used except that 1,4 dimethyl, 2,5 di-ethyl benzene was charged in place of durene. The material charged possessed the following characteristics: R. I., 1.5092 at 20° C.; D₄²⁰, 0.8845; F. P., -32.5° C.; and B. P., 227° C. The air rate was maintained at 53 mols per hour and the hydrocarbon was fed in at 14.4 cc. per hour, while the reactor temperature was maintained at 850° F. A 38.2 weight per cent yield of pyromellitic anhydride of 92.3% purity by neutral equivalent was formed.

Although the product usually will be desired in the anhydride form and should be recovered as such, it is to be understood that the invention is not avoided by recovering the tetracarboxylic acid product in the form of the free acid rather than as the anhydride. In the appended claim, the terms "tetracarboxylic acid product," "polycarboxylic acid product," as distinguished from "tetracarboxylic acid," are used in a generic sense, embracive of the free acid and anhydride forms.

Pyromellitic product may be recovered as the anhydride by condensation from combustion gases or by washing with a solvent. Upon washing the combustion gases with water, for example, the free acid is obtained and may be crystallized from the solution in the form of the dihydrate, i. e., C₆H₂(COOH)₄·2H₂O. Water of crystallization may be removed by heating.

In the oxidation of durene fractions according to this invention, it should be noted that other hydrocarbon impurities are over-oxidized, at least to the point where they are readily separable. Thus, methyl groups are burned off entirely or the ring is ruptured, or both, until by-product impurities differ in major respects from the desired product. This greatly simplifies subsequent final purification. Other impurities, if any, may be removed in suitable fashion. The preferred method of initial purification as herein illustrated is by selective crystallization or condensation of the tetracarboxylic acid anhydride from the mixture of reaction gases.

Obviously, many modifications and variations of the invention as hereinbefore set forth may be made without departing from the spirit and scope thereof, and only such limitations should be imposed as are indicated in the appended claim.

I claim:

A process for oxidizing durene to pyromellitic anhydride, which comprises forming a gaseous mixture of air and durene, the weight of air in said mixture being from 30 to 200 times the weight of durene, contacting the gaseous mix-

ture with a vanadium oxide catalyst disposed on an inert solid support at a temperature in the range 850 to 1050° F. and at a rate such that 0.05 to 3.0 moles of durene are contacted with 50 to 100 cc. of catalyst in one hour.
